UNITED STATES PATENT OFFICE.

JAMES H. JOHNSON, OF LOUISVILLE, KENTUCKY.

ELECTRICAL RECORDING DEVICE.

SPECIFICATION forming part of Letters Patent No. 758,756, dated May 3, 1904.

Application filed July 15, 1903. Serial No. 165,600. (No model.)

To all whom it may concern:

Be it known that I, JAMES H. JOHNSON, of Louisville, in the county of Jefferson and State of Kentucky, have invented certain new and useful Improvements in Electrical Recording Devices; and I hereby declare that the following is a full, clear, and exact description thereof, reference being had to the accompanying drawings, which form part of this specification.

This invention is an improved electrical recording device especially designed for recording railway fares on street - railways, but useful in many other cases where it is desirable to keep track of a number of different transactions. As applied to street-railways the apparatus is designed to record every cash fare, every ticket fare, and every transfer fare received by the conductor, and he may make the record from any desired number of different points on the car by simply pushing a properly-designated button or actuating any other simple device which will close an electrical circuit through the proper selecting and recording devices.

I will now proceed to describe the apparatus as adapted for street-railway indicators, as above suggested, and will refer to the accompanying drawings to illustrate the same, but do not limit myself to the specific constructions of parts shown, as they can be considerably varied to suit the constructor or the particular visual indicator with which the recorder may be connected, while retaining all the essential characteristics of the invention.

In said drawings, Figure 1 is a front view of the recording mechanism, the electrical circuits being indicated diagrammatically. Fig. 2 is a transverse section on line 2 2, Fig. 1; Fig. 3, a longitudinal section on line 3 3, Fig. 1. Fig. 4 is a detail view of the escapement.

A A' are opposite parallel bars mounted on brackets A'. Supported upon and between the bars A A' is a frame composed of end plates B B' and side rods b b'. The end plates are flanged over the outer ends of the bars, and the parallel side rods are connected to the end plates. Rod b is insulated from plate B, and the other rod, b', is insulated from plate B', as indicated in the drawings, for a purpose

hereinafter explained. Plate B, moreover, has a tooth B², which is adapted to be engaged with any one of the notches A³ in bar A, so as to lock the frame against lateral movement thereon, and a spring B⁴ is arranged to hold the plate in engagement with bar A, but permit the plate being moved outward sufficiently to disengage its tooth from the notch and allow the frame to be shifted laterally to a new position.

Slidably hung upon and between rods b b' and guided thereby is a carriage C, having end flanges C', perforated for the passage of rods b b'. On this carriage is mounted a pair of electromagnets D, which actuate the recording device and also the carriage-escapement. The armature D' of the magnets is supported on a rock-shaft d, pivoted between adjusting-screws e on the carriage, and to this shaft is attached a lever E, which extends beyond the end of the carriage and carries a marking-finger E', which is shown merely as a threaded rod tapped through a threaded opening in the end of lever E and provided with a binding-nut e, as shown. The lever E actuates the escapement device of the carriage in one direction each time a record is made by the finger. The escapement mechanism shown comprises a vibrating arm F, connected to a rock-shaft F', pivoted on a hanger C², attached to the carriage. Said arm has a tooth F² on its outer end adapted to engage with the teeth g of a ratchet-bar G, extending beneath the carriage parallel with rods b b' and attached to the end plates B B', as shown, but insulated therefrom. The arm F underlies lever E, and when the latter is depressed by the energization of the magnets D it depresses arm F also. Beside tooth F² is an alternately-acting tooth f², which is pivoted on the end of a swinging arm f, pivoted to arm F so as to swing laterally thereof, tooth f² being so pivoted to the end of arm f that it can swing laterally thereof in one direction, but cannot pass back of the line thereof in the opposite direction and is normally held in alinement with lever f by spring f³. The arms F f are uplifted by a spring F³, as indicated in the drawings, so as to normally hold tooth f² in engagement with one of the teeth of rack-bar G, 100

tooth F^2 standing above the rack-bar, so that when arms F^f are depressed by lever E tooth f^2 will be moved out of engagement with bar G and tooth F^2 into engagement therewith, 5 and when the arms are freed springs F^3 lift arms F^f , disengaging tooth F^3 from the rack-bar, but bringing tooth f^2 into engagement therewith a tooth in advance of that just disengaged by tooth F^2 . Consequently the carriage 10 can advance one step at each depression of lever E and at each record made therein similar to the manner in which the carriage of a type-writer advances. When the carriage and frame are arranged vertically, the carriage 15 will descend by gravity; but if arranged in other positions (not shown) springs may be arranged to pull the carriage forward, as permitted by the escapement mechanism.

Beneath the carriage and in a plane parallel therewith is a table H , which is supported on brackets A^2 and preferably insulated therefrom. On this table lays a movable plate H' , which is provided with paper-holding clips h of any suitable construction, adapted to retain 20 a sheet or sheets of paper S , which sheets are provided with ruled columns, which in example shown are in series of three, marked "Tickets," "Transfers," and "Cash," respectively. When properly adjusted, the "Tickets" column comes under the marker E' , and when a ticket fare is received the proper electrical connection is made to actuate the lever E and record a ticket. If a cash or transfer fare is received, the plate H' and carriage are shifted laterally relatively 25 to each other and in example shown by moving plate H' laterally by suitable magnets and connections before lever E is actuated, so that the fare will be recorded in the proper column. As shown, plate H' is shifted, by means of magnet I or J , in one direction and is turned to normal position by a spring H^3 . The armature I' of magnets I is provided with a finger i , which engages a slotted plate H^2 , attached to plate 30 H' , and will move the plate laterally a certain distance when magnet I is energized. The armature J' of magnets J is provided with a rod j , which loosely engages the slot in plate H^2 and will move the plate h laterally a greater distance 35 than magnets I . Magnets I are electrically connected to buttons representing transfer fares and magnets J to buttons representing cash fares. The electrical connections will of course vary with the location and constructions of the parts, but are sufficiently indicated in the drawings, (see Fig. 1,) where K represents a battery or source of current. k is the main wire, leading from the battery to the different push-buttons, k' is a return-wire 40 leading from the bar A' to the battery. k^2 is a wire leading from the ticket push-button T to the bar A . Consequently when a ticket-button is pressed a circuit will be closed from the battery through wire k^2 , bar A , plate B , rod b , through magnets D to rod b' , plate B' ,

bar A' , and wire k' back to battery, and the energization of magnets D causes the actuation of lever E and the registration of a ticket fare and the movement of the carriage C one step. 70

The magnets I are connected by wire i' to transfer-buttons i^2 and by wire i^3 to bar A . Consequently when a transfer-button is pressed the electrical circuit is closed, first through magnets I and then through magnets D . Therefore plate h is shifted before lever E is depressed, and consequently a record is made in the proper column of the transfer. When the button is released, the parts return to normal position. Magnets J are similarly connected by wire j' to cash-buttons j^2 and through wires j^3 I^3 to bar A . Consequently when a cash-button is depressed the circuit is established through magnets J and D in succession, so that plate h is shifted before lever E descends. Consequently the cash fare is recorded in the proper column. The magnets I and J may be appropriately termed "selective" magnets, as they select or determine the position of the record, so that a particular kind of fare shall be registered thereon. If desired, a gong O may be mounted on the carriage and struck by a hammer o , attached to the armature of magnets D , each time the lever E is actuated, thus giving audible notice of the fare registered. 85 90 95

From the foregoing description the operation of the device will be clearly comprehended. The possibilities of modification in electrical connections is obvious, and it is also obvious that the invention is not restricted to the specific construction and combinations of parts shown and described herein. I have not deemed it necessary to show a casing for the apparatus nor to include herein a description or showing of mechanism for visually indicating the kind of fare registered nor for computing the total number of fares, these devices not being claimed herein, although ordinarily provided with fare-registering apparatus. 100 105 110

The apparatus as disclosed herein can make a permanent office record of each trip and the number and kinds of fare tendered.

While I have shown but two selective armatures for shifting the record-sheet, obviously one or more than two selective armatures can be used, according to the number of different fares or items it is desired to record in different columns. 115

The marking-finger E' may be of a character to mark the paper like an ordinary recording instrument, or it may act like a type-key, marking the paper by striking an interposed carbon sheet or ribbon. None of these 120 arrangements possess patentable novelty, and therefore I do not describe or show them all, but have merely indicated in the drawings a carbon-sheet interposed between the record-sheet and marking-finger, such carbon-sheet 125 130

being removable and insertible with the record-sheets.

Having thus described my invention, what I therefore claim as new, and desire to secure by Letters Patent thereon, is—

1. In a recording device, the combination of a laterally-movable frame, a carriage movable on said frame, and a marking device on said carriage, and mechanism for moving said carriage each time the marker is actuated, with a record-holder beside the frame, and selective devices for variously shifting said record-holder, substantially as described.

2. In a recording device, the combination of a frame, a carriage movable on said frame, a magneto-electric marking device on said carriage, and an escapement mechanism for, moving said carriage each time the marker is actuated, with a record-holder beside the frame, and selective electromagnetic devices for shifting said record-holder, substantially as described.

3. In a recording device, the combination of a frame, having side rods, a carriage slidably mounted on said rods, an electromagnetic marking device on the carriage, and means for transmitting electric currents through the rods and magnets, substantially as described.

4. In a recording device, the combination of a laterally-adjustable frame, having electrically-insulated side rods, a carriage slidably mounted on said rods, an electromagnetic marking device on the carriage and means for transmitting electric currents through the rods and magnets, substantially as described.

5. In a recording device, the combination of a frame, having side rods, a carriage slidably mounted on said rods, an electromagnetic marking device on the carriage, and means for transmitting electric currents through the rods and magnets, with an escapement mechanism for said carriage actuated by the marking device in one movement, and by a spring in the return movement, substantially as described.

6. In a recording device, the combination of a laterally-adjustable frame, having electrically-insulated side rods, a carriage slidably mounted on said rods, an electromagnetic marking device on the carriage, and means for transmitting electric currents through the rods and magnets, with an escapement mechanism for said carriage actuated by the electromagnetic marking device in one movement by a spring in the return movement, substantially as described.

7. In a recording device, the combination of a carriage, a marking device thereon, an escapement mechanism controlled by said marking device, a record-holder below the frame, selective devices for shifting said holder, and means for actuating the marking device independently of, or in connection with a selective device substantially as described.

8. In a recording device, the combination of a carriage, a magneto-electric marking device

thereon, a record-holder below the frame, selective electromagnetic devices for shifting said holder, and means for transmitting electric currents through the magneto-electric marking device alone, or through a selective device and the marking device, substantially as described.

9. In a recording device, the combination of a laterally-adjustable frame, a carriage slidably mounted thereon, escapement for a magneto-electric marking device thereon, a record-holder below the frame, selective electromagnetic devices for shifting said holder, and means for transmitting electric currents through the magneto-electric marking device alone, or through a selective device and the marking device, substantially as described.

10. In combination, a carriage, electromagnets on said carriage, a lever carrying a marking device actuated by said magnets, an escapement mechanism on the carriage, a ratchet-bar on the frame, said escapement mechanism being controlled by the marking device, and means for transmitting electric currents through said electromagnets.

11. In combination, a laterally-adjustable frame, a ratchet-bar thereon, a carriage slidably mounted on said frame, electromagnets on said carriage, a lever carrying a marking device actuated by said magnets, an escapement mechanism on the carriage engaging the ratchet-bar on the frame, said escapement mechanism being moved one way by the marking-lever, and returned by a spring, and means for transmitting electric currents through said electromagnets.

12. In combination, a carriage, electromagnets on said carriage, a lever carrying a marking device actuated by said magnets, an escapement mechanism on the carriage, a ratchet-bar on the frame, said escapement mechanism being controlled by the marking device, and means for transmitting electric currents through said electromagnets, with a shiftable record-holder below the frame, electromagnetic devices for shifting said holder, and means for transmitting currents through the latter magnetic devices, substantially as described.

13. In combination, a laterally-adjustable frame, a ratchet-bar thereon, a carriage slidably mounted on said frame, electromagnets on said carriage, a lever carrying a marking device actuated by said magnets, an escapement mechanism on the carriage engaging the ratchet-bar on the frame, said escapement mechanism being moved one way by the marking-lever, and returned by a spring, and means for transmitting electric currents through said electromagnet, with a shiftable record-holder below the frame, electromagnetic devices for shifting said holder, and means for transmitting currents through the latter magnetic devices, substantially as described.

14. In a recording device, the combination of a carriage, a marking device on said carriage, electromagnetic devices for actuating said marking device, a carriage-escapement mechanism controlled by said magnetic devices; means for sending electric currents through the electromagnets, and with an adjustable record-holder below the frame, substantially as described.
15. In a recording device, the combination of a laterally-adjustable frame having side rods, a carriage slidably mounted on said rods, a vibrating marking-lever on said carriage, and electromagnetic devices for actuating said marking-lever, with a carriage-escapement mechanism controlled by said marking-lever; means for sending electric currents through said electromagnets, an adjustable record-holder below the frame, and means for shifting the holder laterally, substantially as described.
16. In a recording device, the combination of a carriage, an escapement mechanism for said carriage, an electromagnet mounted on the carriage, a marking device actuated by the said magnet, said device controlling the escapement mechanism; means for sending electric currents through said magnet, a plate below the frame, adapted to hold a record in position for marking by the said recording de-
- vice, electromagnetic devices for shifting said plate, and means for transmitting electric currents through the electromagnetic shifting devices and the recording-magnet, substantially as and for the purpose set forth. 35
17. In a recording device, the combination of a laterally-adjustable frame, a carriage thereon movable longitudinally thereof, an escapement mechanism for said carriage moving therewith, an electromagnet mounted on the carriage, a rocking lever actuated by the armature of said magnet, and carrying a marking device, said lever controlling the escapement mechanism; means for sending electric currents through said magnet, a record-carrying plate below the frame, adapted to hold a record in position for marking by the said recording device, selective electromagnetic devices for shifting said plate varying distances, and separate means for transmitting electric currents through either selective electromagnetic device, and the recording-magnet, all substantially as and for the purpose set forth. 40
